US00D633632S

(12) **United States Design Patent**
Culbert et al.

(10) **Patent No.:** **US D633,632 S**
(45) **Date of Patent:** **** Mar. 1, 2011**

(54) **LED LIGHT FIXTURE**

(75) Inventors: **J. Scott Culbert**, Birmingham, AL (US);
Kenneth Martin, Birmingham, AL (US)

(73) Assignee: **Glowble SSL, Inc.**, Birmingham, AL
(US)

(**) Term: **14 Years**

(21) Appl. No.: **29/343,891**

(22) Filed: **Sep. 21, 2009**

(51) LOC (9) Cl. **26-05**

(52) U.S. Cl. **D26/24; D26/72**

(58) **Field of Classification Search** **D26/24,**
D26/67, 72; 362/147, 294.02, 373

See application file for complete search history.
